UNITED STATES PATENT OFFICE.

HARRISON H. EATON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-SUPPORT FOR LASTS.

1,264,287.

Specification of Letters Patent. Patented Apr. 30, 1918.

Application filed September 12, 1916. Serial No. 119,764.

To all whom it may concern:

Be it known that I, HARRISON H. EATON, a citizen of the United States, residing at Beverly, in the county of Essex and State 5 of Massachusetts, have invented certain new and useful Improvements in Heel-Supports for Lasts; and I do hereby declare the following to be a full, clear, and exact description of the invention, such as will enable 10 others skilled in the art to which it appertains to make and use the same.

This invention relates to heel supports for lasts, and more particularly to a protector for heel supports for preventing the 15 lining and upper of a shoe from becoming injured when the last is placed on the heel support.

When the upper of a high shoe or boot is drawn in over the last there is a tendency 20 for the upper and lining, which extend above the top of the last to close in upon the top of the last. For this reason, when the lasted shoe is placed on the heel support of a jack, the upper and lining are often 25 injured by being pinched between the top of the last and the heel support. Several forms of lining protectors have been devised to move the upper away from the top of the last when the shoe is being placed 30 on the heel support. In operation, however, these protectors have not been entirely satisfactory, being somewhat uncertain in their action and liable to damage by the heavy pressures to which the lasts are subjected while on the heel support.

The primary object of the present invention is to provide an improved lining protector for a heel support which will be simple and durable in construction and efficient and certain in operation.

With this and other objects in view, the invention consists in the improved lining protector for heel supports hereinafter described and set forth in the claims.

The various features of the invention are 45 illustrated in the accompanying drawings, in which,

Figure 1 is a view in side elevation of the upper portion of a well known type of sole laying machine, showing a heel support embodying the preferred form of the invention; Fig. 2 is a front elevation; Fig. 3 is a rear elevation; and Fig. 4 is a side ele-

vation of the improved heel support showing the lining protector applied thereto. 55

The heel support illustrated in the drawings consists of a last block 10 to which is secured a spindle 12. The lining protector for this support consists of an enlarged portion 14 on the spindle 12 and a lining 60 and upper spreader 16 which is rotatably mounted upon the enlarged portion. The enlarged portion 14 as shown in the drawings consists of a sleeve which is secured upon the spindle 12 with one end against the last block 10 and the other end forming a shoulder 15 to support the last while it is being operated upon. This sleeve 14, however, may be formed integral with the spindle 12. The spreader 16 is loosely 70 mounted on the sleeve 14 and is connected with the sleeve, so as to have a rotary and longitudinal movement thereon. The rotary movement of the spreader is obtained by means of a pair of diametrically opposed 75 spiral grooves 18 which are formed in the periphery of the sleeve, and a pair of diametrically opposed screws 20 which are mounted in the spreader and have pins 22 which project into the spiral grooves 18. 80 The spiral grooves extend through approximately an arc of 90° and the extent of movement of the spreader on the sleeve is determined by the engagement of the pins 22 with the end of the spiral grooves 18. 85 The spreader is normally held in a position extended toward the end of the spindle by means of a compression spring 24 which is mounted on the sleeve between the last block and the spreader. 90

The preferred form of the invention is illustrated as embodied in the jack of the Goodyear sole laying machine. The jack consists of a cross bar 26 which is supported by uprights 28 and upon the cross bar are 95 mounted a heel post 30 and a toe post 32. A toe rest 34 for engaging the toe portion of the shoe is mounted upon the toe post 32 and the heel support is pivotally mounted upon the heel post 30. A compression spring 100 36 is mounted upon the heel post and the upper end of the last block 10, which normally tends to move the spindle 12 toward the toe rest 34.

The operation of the heel support is as 105 follows: The spring 24 normally holds the

spreader extended toward the end of the spindle, and when the last is placed upon the spindle a pair of diametrically opposed spreading teeth 38 on the spreader will engage the top of the last. In Fig. 2 is illustrated the position which the spreader occupies with reference to the last when the teeth 38 first come into contact with the top of the last. As the last is moved up on the spindle the spreader will be rotated about the sleeve by the spiral groove and pin connection between them. During the movement of the last on the spindle the spreading teeth remain in contact with the top of the last and are rotated from a position longitudinally of the last to a position approximately transverse of the last. When they have come into the transverse position they will have forced the lining away from the spindle so that it cannot be pinched between the sleeve 14 and the top of the last. A difficulty hereinbefore experienced with various forms of lining protectors was due to the fact that the upper surface of the last might be rough or have ridges which would be engaged by the spreading members of the lining protector and hold them from operation. Then when the pressure was placed upon the last, while operating upon the shoe, the lining might be injured or the protector broken.

With the lining protector illustrated in the drawings, it will be noted that the spreading teeth are heavily constructed so that when they are being rotated as the last is forced on to the spindle, if the top of the last is rough they will have sufficient strength to cut or plow their way through the wood to come to the position shown in Fig. 3. It will be seen also that the spreading teeth always remain in contact with the top of the last which will insure that no part of the lining or upper can be pinched between the spreader teeth or the sleeve and the top of the last. When the last has been moved into the position shown in Fig. 3, the weight of the last rests upon the sleeve 14

and not upon the spreader, because the spreader is yieldingly held on the last by the spring 24, and can move up beyond the shoulder 15. Therefore, the spreader cannot be injured by the pressure upon the last while the shoe is being operated upon.

The preferred form of the invention having been thus described, what is claimed as new is:

1. A last heel support having in combination, a last block, a spindle provided with an enlarged portion to form a last supporting shoulder, and a spreader mounted upon said enlarged portion to rotate axially thereof.

2. A last heel support having in combination a last block, a spindle provided with an enlarged portion to form a last supporting shoulder, a spreader on the enlarged portion mounted to move from a position between the last block and the shoulder to a position beyond the shoulder, and a connection between the enlarged portion and the spreader whereby the spreader will be rotated in its movement.

3. A last heel support having in combination, a last block having a spindle provided with an enlarged portion to form a last supporting shoulder, a spreader surrounding said enlarged portion, the enlarged portion having spiral grooves each extending through approximately an arc of 90°, a connection between the spreader and the grooves, and spreading teeth on the spreader for engaging the last while the spreader is being rotated.

4. A last block, a spindle provided with an enlarged portion to form a last supporting shoulder, a spreader mounted on the enlarged portion, a groove and pin connection between the enlarged portion and spreader by which the spreader has a limited rotary motion on the enlarged portion, and a spring mounted between the last block and the spreader to hold the spreader extended beyond the shoulder on the spindle.

HARRISON H. EATON.
